ROCK CRUSHER

Albert Thomas Benson, Horsham, Victoria,
AustraliaApplication November 5, 1938, Serial No. 239,122
In Australia November 5, 1937

3 Claims. (Cl. 83—53)

This invention relates to rock crushers and has for its general object to provide an improved rock crusher capable of operating more efficiently and more economically than existing crushers and also capable of being readily adjusted to suit varying conditions of operation.

A more specific object of the invention is to provide a double acting crusher in which a single pitman co-operating with a stabilizing or anvil device is arranged to actuate substantially simultaneously two swinging jaws located one at each side of the pitman so as to provide a compact apparatus capable of a relatively high rate of output.

15. Another object of the invention is to provide swinging and stationary jaws of improved formation and arrangement that give rise to an efficient crushing action and which tend to prevent choking of the crusher even if overfed with material to be crushed.

Another object is to provide for adjustment of the swinging jaws so that they may be readily set in positions most suitable to varying conditions of operation.

25. The above and other objects of the invention will, however, be more readily appreciated from the following description relating to one practical embodiment of the invention.

Referring to the drawings which form part 30 of this specification—

Figure 1 is a part sectional side elevation of a crusher according to one embodiment of the invention.

Figure 2 is a plan of Figure 1.

35. Figure 3 is a part sectional elevation taken in a plane at a right angle to that of Figure 1.

Figure 4 is an enlarged cross section taken on line IV—IV of Figure 2 and showing an eccentric adjustment device for the swinging jaw.

40. Figure 5 is a section taken on line V—V of Figure 4.

Figure 6 is a cross section taken on line VI—VI of Figure 1.

According to such an embodiment the apparatus includes a suitable frame 2 across the upper part and at about the centre of which a driving shaft 3 extends laterally. The driving shaft has an eccentric portion 4 encircled by the upper end of the pitman 6 which is fitted with ball or roller bearings 7. Similar bearings 7a encircle the end portions of the driving shaft where it projects through bearing bosses 8 on the frame, and bearing caps 9.

The pitman depends within the frame 2 and is provided in its lower part with a slot, recess

or passage 11 to accommodate a square section or straight-sided stabilizer or anvil block or sleeve 12 that extends transversely and is capable of oscillating about a transverse shaft or axle 13 which is stationarily mounted as by having its end portions suitably keyed as at 14 Figure 3, within bosses 16 at opposite sides of the frame. When worn, block 12 and shaft 13 may be given a quarter turn to present new wearing surfaces.

The side faces of the lateral slot or passage 11 of the pitman may be provided with renewable wearing plates 17 that make sliding contact with the side faces of the stabilizer block 12 so that the block may oscillate slightly about axle 13 in conformity with the slight oscillation of the lower end of the pitman which also reciprocates substantially vertically in relation to the block by which it is guided.

By means of this block, the pitman is stabilized and enabled to transmit motion, substantially simultaneously by means of sets of suitable toggles 18, to a pair of swinging jaws 19, located one at each side of the pitman. In this connection it will be apparent that during downward movement of the pitman, jaws 19 will be caused to move substantially simultaneously, or in unison towards the respective stationary jaws. The toggles may as usual be of the kind that break in the event of uncrushable or foreign matter being fed into the crusher. The toggles may bear against the pitman at any suitable position slightly above or on the horizontal centre line of shaft 13. In the usual pitman type single jaw crusher with double toggle plates, the thrust of one toggle against the swinging jaw is balanced by the thrust of the other toggle against the end frame of the machine. In my invention the thrust of one toggle will be partly or wholly balanced by that of the other toggle according to the relative vertical positions of shaft 13 and the points of contact between toggles 18 and pitman 6, and the amount of thrust so balanced is available for useful crushing, any unbalanced portion of the thrusts being resisted by the stabilizer. It is obvious that if shaft 13 and the contact points between toggles and pitman were arranged to be in line horizontally, the motions of the two jaws towards or from their respective co-operating stationary jaws would be simultaneous throughout the whole stroke of the jaws, and the crushing loads on the swinging jaws would be balanced through the toggles. If the contact points referred to were arranged to be not in line with shaft 13 the swinging jaws would have, during portion of the

- stroke, an almost simultaneous movement relatively to one another, and the crushing thrust would be very slightly unbalanced, the out of balance amount of thrust being resisted by the stabilizer. The position of the contact points between toggles and pitman relatively to shaft 13 is therefore selected to give as nearly simultaneous jaw movements as is consistent with practical constructional consideration.
- 10 Plates or guards 21 may be attached to opposite ends of the stabilizer block 12 and the pitman 6, adjacent the sides of the frame 2 as seen in Figure 3 in order to protect the block and the pitman slot 11 from dust and other 15 foreign matter.

The spring or tension means for returning the swinging jaws are, according to this invention, preferably located outside the frame so that they are readily accessible for adjustment and 20 will not impede access to the toggles in the event of the latter breaking. For this purpose each swinging jaw may have extending therethrough a pin 22 which projects sidewardly through a slot 23 in the frame to receive one end of a rod 25 24 that is capable of sliding lengthwise through a guide lug 26 outstanding from the frame. A coiled spring 27 may encircle each rod between the guide lug 26 and an adjustable stop such as a wheel or nut member 28 upon the screw 30 threaded outer end of the rod. The tension of the spring may be adjusted by means of the wheel or nut member.

The stationary jaws 29 are located one at each 35 end of the frame. Each stationary jaw has a convex working face 29a of relatively small uniform radius while the co-operating swinging jaw has a concave working face 19a of relatively large uniform radius and the jaws are so arranged relatively to each other that there is formed between them a crushing chamber 25 of curved formation which decreases progressively in volumetric capacity towards its lower or discharge end. A further characteristic of the chamber so formed is that in its upper portion the angle between the working faces as seen 40 in Figure 1 is such that stone cannot be nipped between them but this angle changes so rapidly in the depth of the chamber that the upper limit of the crushing zone in which stone can be 45 nipped and consequently crushed is sharply defined, and the radii of the respective working faces and the disposition of the faces relatively to one another is such as to fix this upper limit of the crushing zone at about midway of the 50 depth of the chamber. Such a formation of the working faces of the crushing jaws is found to be particularly beneficial in that it provides a most efficient crushing action and also prevents choking of the crusher in the event of overfeeding 55 on account of the sharp definition of the point at which nipping can take place.

The reverse face of each stationary jaw 29 may advantageously be of concave curvature so that the jaw may rest against a convex face 31 60 at the respective end of the frame 2. In order to hold each stationary jaw in position laterally extending bars 32 of substantially wedge form in cross section may extend between the upper and lower surfaces of the stationary jaw and shoulders 33 formed at the upper and lower ends of the convex face 31. These wedge retaining bars may be held in position by bolts 30 passing through the respective end walls 34 of the frame so that upon tightening of the bolts the bars 70 75 produce a wedge action which forces and maintains

the stationary jaw in close contact with the convex face 31 of the frame. While it is preferred to employ two wedge-like retaining bars as aforesaid, one of them could be omitted if so desired.

As the curvature of each stationary jaw is uniform throughout, its position may be reversed at any time, if such should be found necessary or advisable on account of wear or otherwise. The change in position can be readily effected by 10 first slackening and then retightening bolts 30 associated with the wedge plates 32.

The working face 19a of each swinging jaw may be formed by a renewable plate 19b which, like the stationary jaws, is reversible and held in 15 position against a concave face of the main body of jaw 19 by a wedge bar 19c and bolts 19d, the main body of the jaw having upper and lower shoulders 19e that co-operate with plate 19b and the wedge 19c. Another wedge bar 19c could 20 be employed at the lower end of the swinging jaw if so desired.

At each end of each stationary jaw and disposed within the frame of the crusher is a side plate 36, one edge of which is curved to conform 25 to the convex working face of the stationary jaw. These side plates are disposed and suitably secured at the sides of the crushing chamber and abut against the end portions of the respective stationary jaw so that there is no 30 likelihood of any of the material being forced between the plates and the stationary jaw. These plates may be removed and renewed at any time.

Each swinging jaw 19 is suspended from and secured to an overhead transverse spindle 37 35 which oscillates in eccentric gunmetal lined bushes 38 secured in brackets 39 and provision is made whereby the position of the swinging jaw may be adjusted in relation to the companion stationary jaw to suit varying conditions 40 of operation, such, for example, as the nature of the material being crushed or the degree of crushing that is required. For this purpose the bushes 38 (see particularly Figures 4 and 5), which are eccentric to the spindle and which 45 are accommodated by bearing brackets 39 and caps 40 at opposite sides of the frame 2 may be turned. Each eccentric bush may be provided with an outwardly projecting portion having one or more radial holes 41 into which a rod or the 50 like may be inserted to enable the bush to be manually turned in its bearing and thus effect bodily adjustment of the swinging jaw spindle 37 in an arcuate path which causes the swinging jaw to be raised or lowered or moved towards or 55 away from the co-operating stationary jaw. Such an eccentric device thus permits of substantially universal adjustment of the swinging jaw so that it is possible to set it in the precise position that is most beneficial to crushing operations.

To facilitate adjustment of the eccentric bushes 38 and to ensure uniform adjustment of the bushes at opposite ends of their spindle 37 so that the swinging jaw 19 will not become 60 canted or tilted in relation to the stationary jaw, the eccentric bush may be provided around its outer periphery with teeth or serrations 42 that are complementary with a number of teeth or serrations 43 formed on the inner surface of the 70 associated bearing cap 40. The bearing brackets 39, may, however, be devoid of any such teeth, but may be internally recessed or relieved to avoid contact with the teeth of the eccentric bush. To adjust the position of a swinging jaw, 75

the respective two bearing caps are loosened or removed whereupon bars or the like may be inserted into the holes of the eccentric bushes 38 in order to turn them in relation to their bearings and thus vary the position of the swinging jaw spindle 37 as desired. The bearing caps 43 are then reapplied and tightened so as to maintain the bushes and the spindle in their adjusted positions.

10 Suitable provision should be made for lubricating all those parts that are subject to friction. Thus, by way of example, as shown in Figure 1, a pipe 44 may convey oil to a passage 46 formed through the pitman and leading to the working faces of the stabilizer block 12 and the respective wearing plate 17. In the same way other pipes may be led to other wearing surfaces. It is preferable that all lubricating pipes should be fed from a central lubricator 15 having a sight feed to each separate pipe.

20 Having now described my invention what I claim as new and desire to secure by Letters Patent is:

1. In a rock crusher of the swinging jaw type, 25 two stationary jaws facing towards each other, two swinging jaws adapted to co-operate with the respective stationary jaws, a pitman disposed between said swinging jaws, means for operating the pitman to substantially simultaneously move the swinging jaws toward the stationary jaws, toggles extending between opposite sides of said pitman and said swinging jaws, and a stabilizer associated with said pitman to resist out-of-balance thrusts in the event of the swinging jaws not moving precisely simultaneously toward the stationary jaws, said stabilizer comprising a block adapted to oscillate about a fixed axis extending transversely of the pitman adjacent its lower end, said block having straight 30 parallel faces at opposite sides of said axis that make sliding contact with complementary faces that are formed internally of said pitman.

2. In a rock crusher of the swinging jaw

type, two stationary jaws facing towards each other, two swinging jaws adapted to cooperate with the respective stationary jaws, a pitman disposed between said swinging jaws, means for operating the pitman to substantially simultaneously move the swinging jaws toward the stationary jaws, toggles extending between opposite sides of said pitman and said swinging jaws, said pitman being provided near its lower end with a transversely extending slot or passage 10 having straight parallel side faces, and a stabilizer associated with said pitman to resist out-of-balance thrusts in the event of the swinging jaws not moving precisely simultaneously toward the stationary jaws, said stabilizer comprising a 15 block extending lengthwise through said slot or passage and oscillating about a fixed axis coincident with said slot or passage, said block having side faces complementary to and making sliding contact with said side faces of said slot 20 or passage.

3. In a rock crusher of the swinging jaw type, two stationary jaws facing toward each other, two swinging jaws adapted to cooperate with the respective stationary jaws, a pitman disposed 25 between said swinging jaws, means for operating the pitman to substantially simultaneously move the swinging jaws toward the stationary jaws, toggles extending between opposite sides of said pitman and said swinging jaws, said pitman being provided near its lower end with a transversely extending slot or passage having straight parallel side faces, a fixed axle extending lengthwise through said slot or passage, and a stabilizer associated with said pitman to resist out-of-balance thrusts in the event of the swinging jaws not moving precisely simultaneously toward the stationary jaws, said stabilizer comprising a sleeve rotatable about said axle within 30 said slot or passage, and having side faces complementary to and having sliding contact with said side faces of said slot or passage.

ALBERT THOMAS BENSON.
